R. A. McCANN

RAILWAY TRAFFIC CONTROLLING APPARATUS

Filed Aug. 11, 1923

Patented Feb. 19, 1924.

UNITED STATES PATENT OFFICE.

RONALD A. McCANN, OF SWISSVALE, PENNSYLVANIA, ASSIGNOR TO THE UNION
SWITCH & SIGNAL COMPANY, OF SWISSVALE, PENNSYLVANIA, A CORPORATION OF
PENNSYLVANIA.

RAILWAY-TRAFFIC-CONTROLLING APPARATUS.

Application filed August 11, 1923. Serial No. 656,874.

To all whom it may concern:

Be it known that I, RONALD A. McCANN, a citizen of the United States, residing at Swissvale, in the county of Allegheny and 5
5 State of Pennsylvania, have invented cer-
tain new and useful Improvements in
Railway-Traffic-Controlling Apparatus, of
which the following is a specification.

My invention relates to railway traffic 10
controlling apparatus, and particularly to
apparatus of the type wherein governing
means on a vehicle is controlled by energy
received from the trackway.

I will describe one form of apparatus 15
embodying my invention, and will then
point out the novel features thereof in
claims.

In the accompanying drawings, Fig. 1 is 20
a diagrammatic view showing one form of
apparatus embodying my invention. Fig.
2 is a view showing on an enlarged scale
the vehicle carried receiving coils and re-
ceiving circuits shown in Fig. 1. Fig. 3 is 25
a fragmental view showing a modification
of a portion of the apparatus shown in Fig.
1 and also embodying my invention.

Similar reference characters refer to sim-
ilar parts in each of the several views.

Referring first to Fig. 1, the reference 30
characters U and V designate the two main
tracks of a double track railway, the nor-
mal direction of traffic over each track be-
ing indicated by the arrow associated therewith. Leading from the main track V is
35 a branch track 74 which is connected with
the main track by a switch 75. Between
two main tracks U and V is a crossover
73 which is connected with the main tracks
by switches 76 and 77. It will be seen, 40
therefore, that in addition to main line
movements on tracks U and V, an east-
bound vehicle may proceed along main track
V and into the branch track 74, whereas a
west-bound vehicle may pass from the 45
branch track 74 into main track V and
thence through the crossover 73 to the
west-bound track.

The main line tracks U and V are pro-
vided with means for supplying governing 50
energy to vehicles, whereas the branch track
74 is not so equipped. I will therefore term
the main tracks U and V, "positive control
territory," and the branch track 74, "non-
positive control territory." In the drawing

I have shown this equipment on track V 55
only, it being understood that similar equip-
ment is provided for track U but is ar-
ranged for west-bound traffic.

The main track V is divided, by insulated 60
joints 56 in the track rails, into a plurality
of track sections N—P, P—Q, etc., each of
which sections is provided with a track
circuit comprising a source of current and
a track relay. As here shown, the source 65
of current for each track circuit is the
secondary 57 of a transformer designated
by the reference character T with an ex-
ponent corresponding to the location, which
secondary is connected with the track rails 70
through a pole-changer as hereinafter ex-
plained. The primary 58 of each of these
transformers is connected with a transmis-
sion line 59 which is constantly supplied
with alternating current by a generator 60. 75
The relay for each section is designated by
the reference character K with an expo-
nent corresponding to the location, and
comprises a winding 61 connected across
the track rails of the section, and a co-op-
erating winding 62 constantly supplied 80
with alternating current by the secondary
65 of an adjacent transformer X the pri-
mary 58 of which is connected with the
transmission line 59. Each relay includes
a contact 63 which occupies an intermediate 85
position when the relay is de-energized, and
is swung to the right or to the left ac-
cording as track winding 61 is supplied
with current of normal or reverse instan-
taneous relative polarity. 90

Located adjacent the entrance end of each 95
track section is a roadside signal designated
by the reference character L with an ex-
ponent corresponding to the location. Each
of these signals is controlled by the asso-
ciated track relay K in a usual and well
known manner, but inasmuch as the control
of the signal has nothing to do with the
present invention, I have omitted the con-
trolling circuits from the drawings in order 100
to simplify the disclosure as much as pos-
sible. Suffice it to say, that when a track
relay is deenergized, the associated signal
indicates "stop"; when the track relay is
energized by track current of reverse rela- 105
tive polarity (that is, when contact 63 is
swung to the left), the signal indicates
"caution"; and when the relay is energized

by track current of normal relative polarity (that is, when the contact 63 is swung to the right), the signal indicates "proceed."

Interposed in each track circuit between the transformer secondary 57 and the track rails in a pole changer which is designated by the reference character Z with an exponent corresponding to the location. Each of these pole-changers is operated by the adjacent signal 4 in such manner that current of normal relative polarity is supplied to the track rails of the block in the rear when the signal indicates proceed or caution, and current of reverse relative polarity is supplied to the track rails of the block in the rear when the signal indicates stop.

The apparatus thus far referred to is constructed and arranged in accordance with well known principles of railway signaling, and its operation will be understood without further explanation.

Each track section is also provided with means for supplying line current to the track rails. For this purpose a resistance 68^a is connected across the track rails at the entrance end of the section, a second resistance 68^b is connected across the rails at an intermediate point in the section, and a third resistance 68^c is connected across the rails at the exit end of the section. Line current is constantly supplied to the rails of each section between resistances 68^a and 68^b by means of a secondary 67 on the adjacent transformer X, the terminals of which secondary are connected with the middle points of these two resistances, respectively. Line current is also at times supplied to the rails of each section between resistances 68^b and 68^c by a secondary 66 on the adjacent transformer T. One terminal of secondary 66 is constantly connected with the middle point of resistance 68^b, while the other terminal is at times connected with the middle point of resistance 68^c through contact 63 of the track relay K for the section next in advance when the relay is energized in either direction, and also through a contact 64 operated by the signal L for such section next in advance, contact 64 being closed when the signal indicates proceed or caution, and open when the signal indicates stop.

It will be seen from the foregoing, that line current is always supplied to the rear portion of each track section; whereas such current is supplied to the forward portion between resistances 68^b and 68^c when the next section is unoccupied, but not when such section is occupied.

The west-bound main track U is provided with apparatus which is the same as that first described for track V. The only parts of this apparatus which is shown in the drawing are the signals J^p and J^q.

The reference character O designates a railway vehicle, which may be either a car

or a train. Mounted on this vehicle (see Fig. 2) in front of the forward axle are two magnetizable cores 69 and 69^a located directly above the track rails 1 and 1^a, respectively. The cores 69 and 69^a are provided with windings 73 and 73^a which are connected in a receiving circuit a in such manner that the currents induced in these windings by track circuit current from transformer secondaries 57 are cumulative, whereas the currents induced in these windings by line current from secondaries 66 and 67 are in opposition and therefore create no current in circuit a. Also mounted on the vehicle O in a suitable position, such as in the rear of the forward axle, are two other magnetizable cores 70 and 70^a, located directly above the track rails 1 and 1^a respectively. These cores are provided with windings 173 and 173^a, which are included in a receiving circuit b in such manner that the currents induced in these windings by line current in the track rails are cumulative, whereas the currents induced in these windings by track circuit current in the track rails oppose each other and therefore create no current in the circuit b.

The reference character A designates a relay carried by the vehicle O, and which I will term the "main" relay. As here shown, this relay is of the induction motor type, comprising a rotor 2 and two stator windings 3 and 3^a. The windings 3 and 3^a are controlled by the energy created in circuits a and b, respectively, by currents in the track rails. Interposed between the receiving circuit a and the relay winding 3 is an amplifying device 71, and interposed between receiving circuit b and relay winding 3^a is another amplifying device 72. These amplifying devices may be of any suitable form, and they are not illustrated in detail herein because they form no part of the present invention. The rotor 2 of relay A operates three circuit controlling contact fingers 4, 5 and 6. The control of relay A is such that when line current is supplied to the receiving circuit b and track circuit current of normal relative polarity is supplied to receiving circuit a, the contact fingers are swung to the right, which I will term the "normal" position, whereas, when the receiving circuit b is energized and the receiving circuit a is energized by track circuit current of reverse relative polarity the contact fingers are swung to the left, which I will term the "reverse" position.

When either receiving circuit a or b is de-energized, the relay A is de-energized, so that its contact fingers occupy their vertical positions. It will be seen at once from the foregoing that when the vehicle is traveling under a proceed signal, the main relay A is energized in normal direction, and that when the vehicle is traveling under a cau-

tion signal this relay will be energized in reverse direction, whereas, after the vehicle passes the resistance 68^b in a caution block, relay A will become de-energized due to the loss of line current.

The main relay A controls speed governing mechanism represented by the reference character E, which mechanism comprises a high speed magnet H and a medium speed magnet M. The complete mechanism E is not illustrated in the drawing for the reason that it forms no part of the present invention. This mechanism is so constructed, however, that when the high speed magnet H is energized, the vehicle may proceed at full speed, such for example as 60 miles per hour; when the high speed magnet H is de-energized and the medium speed magnet M is energized, the vehicle may proceed at an intermediate speed such as 35 miles per hour; and when both magnets are de-energized a brake application will be incurred if the vehicle exceeds a fixed low speed, such for example, as 15 miles per hour.

The speed governing mechanism E is controlled by the main relay A, and also by an auxiliary relay F, as well as by a manually operable circuit controller D. The auxiliary relay F is slow-releasing in character and is normally de-energized. The circuit controller D, as here shown, is a push button comprising back contacts 7-7^a which are normally closed, and front contacts 8 and 8^a which are normally open but are closed when the button is actuated by the engineer or operator of the vehicle.

The high speed magnet H is provided with a primary circuit controlled by the normal contact 5-5^a of relay A, this circuit being as follows: from terminal B of a suitable source of current, through wires 9, 10, and 11, normal contact 5-5^a of the main relay A, wires 12 and 13, back contact 14-14^a of the auxiliary relay F, wires 51, 15 and 16, back contacts 7-7^a of push button D, wire 17, magnet H, and wires 18 and 19 to terminal C of the same source of current. This circuit is closed only when relay F is open, push button D is in normal position, and the main relay A is energized in normal direction, that is, when traffic conditions in advance of the vehicle are such that un retarded progress of the vehicle is permissible.

The medium speed magnet M is controlled by a reverse contact 5-5^b of relay A, the circuit for this magnet being from terminal B, through wires 9, 10 and 11, contact 5-5^b, wire 20, magnet M, and wires 21 and 19 to terminal C. This circuit will, of course, be closed only when the vehicle is proceeding under a caution indication.

In the form of apparatus here shown the vehicle is further provided with a cab signal S comprising four electric lamps G, Y, R and W. The lamps G, Y and R are con-

trolled by the main relay A in such manner as to indicate traffic conditions in advance; the lamp G when illuminated indicates "proceed" or high speed, the lamp Y when illuminated indicates "caution" or medium speed, and the lamp R when illuminated indicates "low" speed. The fourth lamp W is what I will term a "cut-out" lamp, and is provided to indicate to the engineer when the speed governing mechanism E is cut out of service as hereinafter explained.

The circuit for the high speed cab signal lamp G is from terminal B, through wires 9 and 28, normal contact 4-4^a of relay A, wire 22, lamp G, and wires 23 and 24 to terminal C. The circuit for the medium speed lamp Y is from terminal B, through wires 9 and 28, reverse contact 4-4^b of relay A, wire 25, lamp Y, and wires 26, 27 and 24 to terminal C. The circuit for the low speed lamp R is from terminal B, through wires 9, 10 and 29, back contact 6-6^a, wires 30 and 31, back contact 32-32^a of relay F, wire 33, lamp R, and wires 34, 27 and 24 to terminal C. It will be seen, therefore, that lamp G is lighted when relay A is energized in normal direction, lamp Y is lighted when relay A is energized in the reverse direction, and lamp R is lighted when relay A is de-energized, provided that relay F is also de-energized.

The auxiliary relay F is provided with a pick-up circuit which passes from terminal B, through wires 9, 10 and 11, normal contact 5-5^a of relay A, wires 12 and 38, contacts 8-8^a of push button D, wires 39, 40 and 41, winding of relay F, and wire 42 to terminal C. It will be observed that this circuit can be closed only when the main relay A is energized in normal direction. The auxiliary relay F is further provided with a stick or holding circuit which passes from terminal B, through wires 9, 10 and 29, back contact 6-6^a of relay A, wires 30 and 31, front contact 32-32^b of relay F, wires 43 and 41, winding of relay F, and wire 42 to terminal C. This circuit can be closed only when relay F is closed and relay A is de-energized.

When relay F is closed an auxiliary circuit for the high speed magnet H is closed, which circuit passes from terminal B, through wires 9, 10 and 29, back contact 6-6^a of relay A, wires 30, 35, 49 and 50, front contact 14-14^b of relay F, wires 51, 15 and 16, back contacts 7-7^a of push button D, wire 17, magnet H, and wires 18 and 19 to terminal C. It follows, therefore, that while relay F is closed and relay A is de-energized, the vehicle may proceed at full speed. At such times, that is, while relay F is closed, the white lamp W of the cab signal S is lighted by virtue of a circuit which passes from terminal B, through wires 9, 10 and 29, back contact 6-6^a, wires 130

30 and 35, front contact 36 of relay F, wire 37, lamp W, and wires 27 and 24 to terminal C. This lamp then gives the engineer or driver of the vehicle a constant indication 5 of the fact that the automatic control of the vehicle is eliminated.

Reverting to the positive control apparatus associated with track V, it will be noted that a proceed indication is given when the 10 relative instantaneous polarity of the track circuit current on the right-hand rail is normal at the same instant that the relative instantaneous polarity of the line current ahead of the vehicle is normal. Similarly, 15 a proceed indication would be given when the relative instantaneous polarity of the track circuit current on the right-hand rail is reverse at the same instant that the relative instantaneous polarity of the line current 20 ahead of the vehicle is reverse. A caution indication is given, however, when the relative instantaneous polarity of the track circuit current on the right-hand rail is normal at the same instant that the relative 25 instantaneous polarity of the line current ahead of the vehicle is reverse, and vice versa.

The branch track 74 is provided adjacent the main track V with two short track sections 30 78-79 and 79-80, each of which may, for example be approximately 90 feet long. Track circuit current is constantly supplied to short section 78-79 by a transformer 80 which is located adjacent the left-hand end 35 of this section, whereas section 79-80 is constantly supplied with track circuit current by a transformer 82 located adjacent the right-hand end of the section. Line current is constantly supplied to section 40 78-79 by a secondary 88 of a transformer 81, the terminals of which secondary are connected with resistances 84 and 85 bridged across the rails adjacent the two ends of the section. The other section 45 79-80 is constantly supplied with line current by a secondary 89 on transformer 81, which secondary is connected with resistances 86 and 87 bridged across the rails adjacent the two ends of the section. The primaries of transformers 80, 81 and 82 are all connected across the transmission line 59.

The transformers 80, 81 and 82 are so connected with the rails of sections 78-79 and 79-80, that in the first of these sections the track circuit current in the upper rail is normal at the same instant that the line current at the left-hand end of the section is reverse, whereas in section 79-80 the track circuit current in the upper rail is reverse at the same instant that the line current at the left-hand end of the section is reverse. It follows, therefore, that a train 60 passing from track V to the track 74, that is, from positive control territory into the non-positive control territory, will receive a pro-

ceed indication while passing through the short section 79-80; whereas a train passing from track 74 into track V, that is, from non-positive control territory into positive control territory, will receive a caution indication in short section 78-79. 70

The operation of the apparatus in so far as traffic through the main tracks U and V is concerned, will be readily understood from the foregoing without further explanation, it being noted that during such operation the auxiliary relay F performs no function. 75

I will now assume that vehicle O proceeds through track V to switch 75 and thence into the branch track 74. Assuming that section P-Q and the section to the right of Q are unoccupied, the vehicle will receive a proceed indication until it reaches insulated joints 78 in track 74. In section 78-79 the 80 vehicle will receive a stop indication, but this section is so short that the brakes will not be applied even though the circuit for magnet H is open at contact 5-5^a while passing through this section. In section 79-80 the vehicle will receive a proceed indication and while in this section the engineer will reverse push button D, thereby closing the pick-up circuit for relay F. The push button D must be held in the reverse position until the vehicle passes point 80, that is, until relay A becomes de-energized. When this occurs the holding circuit for relay F is closed because back contact 6-6^a of relay A is then closed and contact 32-32^b of relay F is already closed. Push button D may then be released and relay F will remain energized. The auxiliary circuit for the high speed magnet H is then closed, so that even though relay A is de-energized the vehicle may proceed into and through the non-positive control territory 90 95 100 105 74 at full speed without incurring an automatic application of the brakes.

Inasmuch as both circuits for the high speed magnet include the back contact of the push button D, it follows that magnet H is de-energized while this push button D is held in the reverse position by the engineer, as well as while the vehicle is passing 110 through the short section 78-79, as pointed out above. The speed governing and brake control mechanism E is so designed, however, that if magnet H is not de-energized for a time interval greater than that determined by a "delayed brake application" device, the brakes will not be applied. This delayed brake application device forms no part of the present invention, and, consequently, is not illustrated in the drawing. 115 Such a device is fully disclosed in United States Letters Patent No. 1405552, granted to Frank H. Nicholson on Feb. 7, 1922, for railway traffic controlling apparatus. It is sufficient for purposes of the present dis- 120 125 130

closure to state that by virtue of this device an automatic application of the brakes, due to de-energization of magnet H, is delayed for an interval of time which is approximately inversely proportional to the actual speed of the vehicle.

It will be noted that the pick-up circuit of relay F includes a normal contact of relay A but not a reverse contact or a middle contact of this relay. The reason for this is fully explained in an application by L. V. Lewis and Frank H. Nicholson, filed in the United States Patent Office on Feb. 15, 1922, Serial No. 536787. It follows from this that the engineer can close relay F only when passing through a section giving a proceed indication into a section giving a stop indication. Consequently, if section Q or the section to the right of Q were occupied when the vehicle O enters track 74, it would, in the absence of short section 79—80, be impossible for the engineer to pick-up relay F, and so it would be impossible for him to cut out the speed governing apparatus. Owing to the apparatus associated with section 79—80, however, I am assured that a vehicle entering track 74 will always receive a proceed indication very shortly after leaving track V, so that the engineer, if alert, is always able to cut out the speed governing mechanism by proper manipulation of the push button D.

When the vehicle passes from track 74 into the main track V, it will receive no indication in short section 79—80, because the track transformer 82 is short-circuited by the vehicle immediately after entering this section. In section 78—79, however, the vehicle will receive a caution indication, thereby closing relay A in reverse direction, and so cutting the speed governing mechanism into service. One reason for giving only a caution indication in this section 78—79 is to prevent the driver from cutting the speed governing mechanism out of service on passing point 78 if the track between point 78 and the crossover 73 is not equipped with means for supplying vehicle governing energy. The vehicle may then proceed through crossover 73 into the west-bound track U, and as soon as it enters this track it will receive an indication depending on traffic conditions to the left of switch 76.

Referring now to Fig. 3, I have here shown a modified form of apparatus for supplying the short sections 78—79 and 79—80 of track 74 with vehicle governing energy. The demarcation between these sections is in this modification provided by a bond 83 of low resistance connected across the track rails at point 79. Track circuit current is supplied to the sections by transformers 80 and 82, as in Fig. 1, but line current is supplied to both sections by a transformer 81^a, one terminal of which is

connected with the resistance 84 at the left-hand end of the section, and the other terminal of which is connected with resistance 87 at the right-hand end of the section. It will be noted from the plus and minus signs applied to this view, that a vehicle moving toward the right, that is, away from positive control territory, will receive a proceed indication between points 79 and 80, whereas a vehicle moving toward the left, that is, toward positive control territory, will receive a caution indication between points 78 and 79. One advantage of the structure shown in Fig. 3 is that it eliminates the necessity for insulated joints at point 79. In so far as vehicle movements are concerned, the operation of the apparatus shown in Fig. 3 is the same as the operation of the corresponding portion of the apparatus shown in Fig. 1.

It may be desirable in some instances to provide means under the control of the engineer for closing relay F after entering non-positive control territory or after an emergency event, such as the failure of power or the failure of some part of the electrical apparatus. This may be accomplished by a slow-acting manually operable circuit controller J and an auxiliary pick-up circuit for relay F controlled by front contacts 45—45^a of this circuit controller, all as explained in the hereinbefore mentioned application Serial No. 536787, filed by Lewis and Nicholson on Feb. 15, 1922.

Although I have herein shown and described only two forms of apparatus embodying my invention, it is understood that various changes and modifications may be made therein within the scope of the appended claims without departing from the spirit and scope of my invention.

Having thus described my invention, what I claim is:

1. Railway traffic controlling apparatus comprising positive control territory equipped with means for supplying track circuit and line energy to vehicles and non-positive control territory not so equipped, said means being arranged to supply track circuit and line energy of one instantaneous relative polarity or the other according to proceed or caution traffic conditions, two short sections of track adjacent the junction of said territories, means associated with the section nearer to the positive control territory for supplying track circuit and line energy of caution relative polarity to vehicles moving toward the positive control territory, and means associated with the other short section for supplying track circuit and line energy of proceed relative polarity to vehicles moving away from the positive control territory.

2. Railway traffic controlling apparatus comprising positive control territory

- equipped with means for supplying vehicle governing energy to vehicles, and non-positive control territory not so equipped, said means being arranged to supply energy of one relative polarity or the other according to proceed or caution traffic conditions, two short sections of track adjacent the junction of said territories, means associated with the section nearer to the positive control territory for supplying energy of caution relative polarity to vehicles moving from non-positive into positive control territory, and means associated with the other short section for supplying energy of proceed relative polarity to vehicles moving from positive control into non-positive control territory.
3. Railway traffic controlling apparatus comprising positive control territory equipped with means for supplying vehicle governing energy to vehicles and non-positive control territory not so equipped, said means being arranged to supply energy of one relative polarity or the other according to proceed or caution traffic conditions, a vehicle provided with a main relay controlled by energy received from the trackway and energized in normal or reverse direction according as such energy is of proceed or caution polarity, speed governing mechanism controlled by said relay for permitting high, medium or low speed according as the relay is energized in proceed or caution direction or is de-energized, an auxiliary relay on said vehicle, a pick-up circuit for said auxiliary relay including a manually operable circuit controller and a proceed contact of said main relay, a holding circuit for said auxiliary relay including a contact closed when said main relay is de-energized, means for causing said speed governing mechanism to permit high speed when said auxiliary relay is energized, two short sections of track adjacent the junction of said positive and non-positive control territories, means associated with the section nearer to the positive control territory for supplying energy of caution relative polarity to vehicles moving from the non-positive to the positive control territory, and means associated with the other short section of track for supplying energy of proceed relative polarity to vehicles moving from positive to non-positive control territory.
4. Railway traffic controlling apparatus comprising positive control territory equipped with means for supplying vehicle governing energy of one relative polarity or the other according to proceed or caution traffic conditions, a vehicle provided with a main relay controlled by energy received from the trackway and energized in normal or reverse direction according as such energy is of proceed or caution relative polarity, a normally de-energized auxiliary relay on said vehicle, a manually operable circuit controller on said vehicle having a normally closed back contact and a normally open front contact, governing mechanism on the vehicle normally requiring that the main relay be energized in normal direction and the back contact of said circuit controller be closed to give a proceed indication, means for closing said auxiliary relay when the front contact of said circuit controller is closed and said main relay is energized in normal direction but not when said main relay is energized in reverse direction, means for subsequently keeping said auxiliary relay closed if the main relay is de-energized, means effective to give a proceed indication on the vehicle when said main relay is de-energized provided said auxiliary relay and the back contact of said circuit controller are closed, two short sections of track adjacent the junction of said positive and non-positive control territories, means associated with the section nearer to the positive control territory for supplying energy of caution relative polarity to vehicles moving from the non-positive to the positive control territory, and means associated with the other short section of track for supplying energy of proceed relative polarity to vehicles moving from positive to non-positive control territory.
5. Railway traffic controlling apparatus comprising positive control territory equipped with means for supplying vehicle governing energy of one relative polarity or the other according to proceed or caution traffic conditions and the branch track not being so equipped, two short sections of track in the branch track adjacent the main track, means associated with the short section nearer the main track for supplying energy of caution relative polarity to vehicles approaching the main track, and means associated with the other short section for supplying energy of proceed relative polarity to vehicles leaving the main track.
6. Railway traffic controlling apparatus comprising a main track and a branch track, the main track being equipped with means for supplying track circuit and line energy to vehicles and the branch track not being so equipped, said means being arranged to supply track circuit and line energy of one instantaneous relative polarity or the other according to proceed or caution traffic conditions, two short sections of track in the branch track adjacent the junction of said two tracks, means associated with the section nearer to the main track for supplying track circuit and line energy of caution relative polarity to vehicles approaching the main

track, and means associated with the other section for supplying track circuit and line energy of proceed relative polarity to vehicles moving away from the main track.

- 5 7. Railway traffic controlling apparatus comprising a main track and a branch track, the main track being equipped with means for supplying track circuit and line energy to vehicles and the branch track not being so equipped, said means being arranged to supply track circuit and line energy of one instantaneous relative polarity or the other according to proceed or caution traffic conditions, two short sections of track in the
- 10 branch track adjacent the junction of said two tracks, said sections being demarcated by
- 15

a bond of low resistance connected across the rails, a track transformer at each end of the said sections, a line transformer connected with both rails at one end of said sections 20 and also with both rails at the other end of said sections, said track and line transformers being of such relative polarities that a vehicle approaching the main track receives energy of caution relative polarity while in 25 the section nearer to the main track, whereas the vehicle leaving the main track receives energy of proceed relative polarity while in the other section.

In testimony whereof I, affix my signature.

RONALD A. McCANN.
